AWARD TROPHY

William A. Borba, South San Francisco, Calif.

Application July 16, 1949, Serial No. 3,955

Term of patent 14 years

(Cl. D29—23)

To all whom it may concern:

Be it known that I, William A. Borba, a citizen of the United States of America, residing at 524 Spruce Avenue, South San Francisco, California, have invented a certain new, original, and ornamental Design for an Award Trophy, of which the following is a specification, reference being had to the accompanying drawing:

Fig. 1 is a front elevational view of an award trophy showing my new design; and

Fig. 2 is a top plan view thereof.

The dominant features of my design reside in the portions shown in full lines.

I claim:

The ornamental design for an award trophy, substantially as shown and described.

WILLIAM A. BORBA.
